FIG. 7

28

This technical drawing shows a cross-sectional view of a mechanical assembly. The drawing is labeled with various numbers: 25, 25, 25, 20, 18, 25, 25, 22, 23, 2, 19, 1, 2, 19, 2, 23, 6, e, d, c, 122, 123, 5, FIG. 10, and FIG. 11. A cross-hatched area is present on the right side of the drawing, with the number 31 written above it. The drawing is divided into two main sections, labeled FIG. 10 and FIG. 11, with a central vertical line separating them.

JOHN SELLERS BANCROFT, OF PHILADELPHIA, PENNSYLVANIA, ASSIGNOR
TO LANSTON MONOTYPE MACHINE COMPANY, OF PHILADELPHIA,
PENNSYLVANIA, A CORPORATION OF VIRGINIA.

TYPE-MOLD.

SPECIFICATION forming part of Letters Patent No. 752,814, dated February 23, 1904.

Application filed May 29, 1903. Serial No. 159,363. (No model.)

To all whom it may concern:

Be it known that I, JOHN SELLERS BANCROFT, a citizen of the United States, residing at Philadelphia, county of Philadelphia, State of Pennsylvania, have invented certain new and useful Improvements in Type-Molds; and I do hereby declare the following to be a full, clear, and exact description thereof, reference being had to the accompanying drawings, forming a part of this specification, and to the figures of reference marked thereon.

The present invention, although in several particulars applicable to other varieties of molds, is specially designed for use upon or in connection with that class of molds employed in type casting and setting machines for giving form and dimension to type-bodies; and it has for its objects to enlarge the capacity of such molds and facilitate their adjustment or adaptation to different sizes of type-bodies, to increase the stability of the mold as a whole after adjustment and under varying conditions of use, to reduce cost of construction with an increase rather than at a sacrifice of accuracy, and to improve the character of the product.

For well-recognized practical reasons it is required that commercial type shall be of uniform or standard length, (height,) with the body portion rectangular in cross-section and provided with parallel opposite sides. Variations are permitted and, in fact, required as to two dimensions to accommodate different faces, one of said dimensions being uniform for each font or style of characters and the other variable to suit different widths of characters in the same font. In the production of such articles by casting not only is great skill and care required in constructing the mold of proper dimensions with straight parallel walls, but its stability under conditions of use is a factor of equal importance, for the slightest variations in the forms or relative positions of the casting-faces will be reproduced in the type. When to these conditions are added capacity for variation or adjustment as to two dimensions, the one fixed with relation to a given font or series of characters and the other varia-

ble at will or automatically to accord with the different width of characters occurring in the same font, the difficulties confronting the mold maker are correspondingly increased, especially if economy and durability are also to be taken into account. Attempts have heretofore been made to produce molds of this character for use in connection with type casting and composing machines such as those of Patents Nos. 633,088 and 625,998; but they have heretofore been unsuccessful either by reason of cost of production, difficulty of adjustment, or inaccuracy and lack of stability under different conditions of use, all of which objections are sought to be removed or overcome by the present invention, as hereinafter fully described, the novel features being pointed out in the appended claims.

In the accompanying drawings, illustrating a preferred form of embodiment of said invention, Figure 1 is a perspective view of the mold. Fig. 2 is a partial horizontal section. Fig. 3 is a vertical section on line *a-a* of Fig. 2. Fig. 4 is a section on the line *b-b*, Fig. 1. Fig. 5 illustrates a modified form of adjusting means for holding the mold-blade to position. Fig. 6 is a detail view showing one corner of the mold. Fig. 7 is a rear elevation. Fig. 8 is a side elevation, and Fig. 9 is a bottom plan view, of the mold. Fig. 10 is a partial vertical section on the line *c-c*, Fig. 7. Fig. 11 is a partial vertical section on the line *d-d*, Fig. 7. Fig. 12 is a partial vertical section on the line *e-e*, Fig. 7. Fig. 13 is a bottom view of the intermediate or filling piece, carrying the blocks forming the side walls of the mold-cavity. Fig. 14 is a top view of the portion of the bottom plate receiving the intermediate support, Fig. 13.

Like numerals of reference in the several figures indicate the same parts.

The base-section 1, preferably rectangular in outline, has its upper surface dressed flat to serve as a base-line for the erection of the separate members, and its lower surface is furnished with projecting bearings 2, preferably three in number and disposed in triangular relation, the surfaces of said bearings

being dressed to a plane parallel with the upper surface of the base. The object in thus providing the base-section with a plurality of supporting-bearings instead of a continuous plain surface is to facilitate the correct seating of the mold upon its support and to diminish cost of construction.

A slight warping of the supporting-surface or the presence of fragments of metal or dirt 10 will prevent a proper seating of a plane surface when it would afford an ample support for the projecting bearings. Moreover, corrections for slight warpage incident to the hardening process can the more readily be effected.

It is to be borne in mind that in this class of molds, wherein the centering of the matrix is accomplished independently of, but with relation to the mold, the matrices being applied one at a time to the upper face of the mold and seated thereon to close one end of the mold-cavity metal-tight, it becomes very desirable that the face of the mold with which the matrix contacts should stand in a plane 20 perpendicular to the axis of the matrix and of the mold-cavity. Hence the desirability of a level and firm seating of the mold.

Upon the upper face of the base-section 1 is mounted the rectangular parallel-sided block 3, whose upper face supports the side blocks 4 and 5 and mold-blade 6, the reciprocating cross-blade 7, provided with offset 8, containing the jet opening or passage 9 and the ejector 10, the block 11, to which is attached the 30 adjustable guide 12, and the ejector-cam 13, all these parts, with the exception of the means for adjustment and attachment to be presently described, being substantially the same as the corresponding elements disclosed in the mold 40 of Patent No. 625,998 and adapted to similar uses. In this particular style of mold the intermediate block 3 serves merely to elevate the mold-cavity above the offset 8 of the cross-blade to form and sever the jet; otherwise it 45 would not be required, and the side blocks and mold-blade may contact directly with the base-section or other intermediary.

The front wall of the mold-cavity is supplied by the side of cross-blade 7, the side walls 50 by the side blocks 4 5, and the rear wall by the mold-blade 6. The intervals between the proximate faces of the side blocks determines one dimension of the mold-cavity, corresponding to height columnwise of the character, 55 while that between the proximate faces of the cross-blade and mold-blade determines another dimension in a plane at right angles to the first.

In order to produce square-bodied type with 60 parallel opposite faces, it is required that the proximate faces of the side blocks 4 5 should be maintained in parallel planes and that a change in the relation of the side blocks for dimensioning the mold and involving a substitution of mold-blades should involve a cor-

relative adjustment of both side blocks in order to properly position the mold-cavity relatively to the centering-point of the matrix, inasmuch as the latter is not determined or affected directly by any adjustment of the 70 mold itself. To accomplish this and at the same time preserve the desired parallelism of the opposite faces of the mold-cavity, the following arrangement has been devised. Each side block 4 5 has its molding and rear faces 75 formed accurately at right angles, one to another and perpendicular to its lower surface, the latter contacting with the flat surface of block 3, to which it is secured in a manner to permit limited lateral adjustment, as by screws 80 14 or 15. Block 3 is in turn adjustably secured to the base-section, as by screws 16, and to insure additional strength and rigidity fastening devices, such as screws 17, connect the base-section 1 and side blocks 4 5 in a manner 85 to cause the latter to engage and press block 3 upon the upper surface of the base. Thus ample provision is made for permitting either independent or simultaneous 90 adjustments of the side blocks in a plane parallel with the upper surface of the base-section for maintaining the molding-surfaces perpendicular to the base under all conditions and for firmly clamping and holding the side blocks. To preserve the parallelism of the molding- 95 surfaces in the other direction, while permitting adjustment and increasing the rigidity of the mold, the rear faces of the side blocks 4 5 are engaged by the flat surface of a bar or block 18, the latter engaging the rear face of 100 block 3 and the upper surface of the base-section 1, to which it is secured by screws 19 in a manner to permit horizontal adjustment. This block 18 is secured to block 3 and side blocks 4 5 by screws 25, and it operates to 105 align the rear faces of the side blocks. Said block 18 is provided with a recess 20 for the passage of the mold-blade and carries the adjustable stops 21 for limiting its forward movement.

Competent means are supplied for effecting the horizontal adjustment of the side blocks relatively to each other and longitudinally of the block 18 to both dimension the mold-cavity and position the latter and for adjusting 115 block 18 in conjunction with block 3 and side blocks 4 5 for effecting a bodily shift of the mold-cavity relatively to the centering-point of the matrix, so as to bring the mold-cavity in proper relation to the matrix-cavity for 120 different fonts, this adjustment being permitted by a corresponding adjustment of guide 12.

The form of adjusting means shown for shifting the block 18 consists of two pairs of 125 screws 22 23 at each end of said block, of which the one, 22, is threaded into the block with its head overlapping and engaging base-section 1, while the other, 23, is threaded into the base-section and its head engages block 18. 130

By loosening one screw and tightening the other either or both ends of the block 18 can be advanced or retracted upon the base-section. A similar means of adjustment (screws 122 and 123) is interposed between the end of block 18 and side block 5 for regulating the position of the latter.

The side blocks 4, 5, when adjusted to dimension the mold are fixed in position, whereas the mold-blade 6 is a movable member whose position is shifted at will or automatically to vary the other dimension of the mold-cavity. This requires that the mold-blade should be of the proper thickness to form a metal-tight joint with the side blocks and at the same time be free to reciprocate. Heretofore it has been the practice to employ the mold-blade as a gage in setting the side blocks; but this practice is open to serious objection, as a certain degree of clearance between the mold-blade and the side blocks is required, for if the latter are set up too tight the mold-blade will be prevented from moving or become "bung up," as it is termed, and if set too far apart the joints will be opened sufficiently to permit the passage of molten metal, thereby not only clogging the guideway, but producing fins on the type-body.

Another defect of the prior mold was the cutting away of the mold-blade for the accommodation of a cross-piece applied to the tops of the side blocks for connecting the latter and forming a guide or bearing for holding the mold-blade down upon its seat on block 5.

It is of course necessary that some means be employed for sustaining the mold-blade against vertical displacement; but it was found in practice that the removal of metal from the upper edge so weakened the mold-blade that the upper portion of its casting-surface was liable to be sprung or displaced under the pressure of the injected metal, thus destroying the parallelism of the opposite sides of the mold-cavity to such an extent that the type produced would possess tapering instead of parallel opposite sides. To avoid this, the body of the mold-blade is made of full height, and a longitudinal central opening 26 is formed for the reception of the holding-down guide, and instead of employing the mold-blade for adjusting the side blocks a separate gage-plate is supplied. In the present instance these two functions are joined in a single block 27, inserted in the opening 26 and against which the side blocks 4, 5 are tightly clamped.

The gage 27 is dimensioned as to width to correspond with the particular set or font of type to be cast, so that when the side blocks 4, 5 are tightly clamped upon it the mold-cavity will be exactly of the required width.

The mold-blade, of which there is one for each number or size of gage, is made of the proper thickness proportionally to the gage to afford the requisite clearance without binding or permitting escape of metal.

In its capacity as top guide for the mold-blade the lower edge of the gage is caused to engage and bear upon the lower wall of the slot or opening 26, suitable adjusting means being supplied for the purpose.

To still further brace the side blocks against lateral displacement and provide a convenient means for setting them up against the interposed gage 27 during initial adjustment, the side blocks are bored or drilled for the reception of a rod or bolt 28, one end of which is screwed or otherwise secured to block 5, while the opposite end carries a nut 29 in engagement with the end of block 4. This bolt 28 passes through the opening in the mold-blade 80 and may be utilized as part of the adjusting means for setting the gage in its capacity as top guide for the mold-blade. Thus, as illustrated in Figs. 2 and 4, the bore of the opening within the side block is slightly enlarged 85 next the mold-blade, the bolt passes through the gage, and a screw 30 is arranged to impinge upon bolt to spring it slightly, and thus depress the gage to hold the mold-blade to its seat. An equivalent means for effecting this adjustment of the gage or holding-down guide 27 is illustrated in Fig. 5, wherein the holding-bolt is furnished with a tapered portion engaging the lower face of a tapering or inclined seat in the block 27 for forcing the latter down upon the mold-blade.

A water-circulation system similar to that of Patent No. 625,998 is employed but not illustrated.

The molding-surfaces of the cross-blade and side block 4 are preferably formed flat and true, as heretofore, but those of block 5 and the mold-blade are slightly roughened as by the action of a coarse file or grinder, the object being to produce type-bodies slightly 100 roughened on two of their surfaces to prevent rising and facilitate locking up in the form. This roughening of the surfaces is not of a character or depth to afford openings for the escape of metal. At the same time it produces 105 on the type-bodies a series of biting-ridges, which, contacting with the smooth face of adjacent type, overcomes the tendency to rise when subjected to lateral pressure as in a form.

From the foregoing detailed description it 110 will be apparent how the various adjustments are performed. To diminish the mold in one direction, the proper gage and mold-blade are inserted between the side blocks, the gage is set down upon the mold-blade, and the side 115 blocks clamped rigidly upon the gage. As a preliminary to this adjustment the side block 4 and alining-block 18 are adjusted to bring the mold-cavity in proper relation to the centering-point of the matrix, or these adjustments may be made after the side blocks have 120 been clamped together upon the gage, after which the holding-screws are tightened and the mold-blade rendered rigid, with the exception of the cross-blade, which is movable 125 130

for the discharge of the type, and the mold-blade which is movable to dimension the mold-cavity.

Having thus described my invention, what I claim as new, and desire to secure by Letters Patent, is—

1. In a type-mold such as described the combination with the side blocks and cross-blade, of a mold-blade provided with a central longitudinal opening and a brace extending through said opening and engaging the side blocks; substantially as described.
2. In a type-mold the combination with the side blocks and mold-blade, the latter provided with a transverse opening, of a dimensioning-gage located within said opening in the mold-blade; substantially as described.
3. In a type-mold the combination with the stationary side blocks and a movable mold-blade, of a gage interposed between the side blocks and located within an opening in the mold-blade; substantially as described.
4. In a type-mold the combination with the side blocks of a movable mold-blade provided with a central longitudinal opening and a guide located within said opening and engaging the mold-blade, to hold the latter to its seat; substantially as described.
5. In a type-mold the combination with the side blocks and mold-blade, the latter provided with a transverse opening, of a dimensioning-gage located within said opening and contacting with the side blocks and the mold-blade; substantially as described.
6. In a type-mold the combination with the side blocks and apertured mold-blade, of a dimensioning-gage and mold-blade guide located within the opening in the mold-blade and engaging the side blocks, and means for adjusting said gage to contact with the mold-blade; substantially as described.
7. A type-mold such as described provided with side blocks; an aperture mold-blade; a dimensioning-gage interposed between the said blocks and located within the aperture in the mold-blade; and a bolt connecting the side blocks and extending through said gage provided with adjusting means for shifting said gage into contact with the mold-blade.

8. In a type-mold the combination with the side blocks, apertured movable mold-blade and supporting-block, of a dimensioning-gage extending transversely through the mold-blade and engaging the side blocks, and a bolt connecting the side blocks and extending through said gage; substantially as described.

9. The combination to form a type-mold such as described of the base-section, the intermediate block the side blocks adjustably secured to said intermediate block, the movable mold-blade, the alining-block adjustably secured to the side blocks, and adjusting devices intermediate the base-section and said alining-block for shifting the latter and side blocks, upon the base-section; substantially as described.

10. A type-mold such as described comprising a base-section, an alining bar or block, means for laterally adjusting said alining-bar upon the base-section, side blocks engaging said alining-bar, means for adjusting the side blocks longitudinally of said alining-bar, a dimensioning-gage intermediate the side blocks, and means for securing said elements rigidly in adjusted position.

11. A type-mold such as described comprising a base-section provided with a plurality of seating projections or surfaces; an alining-bar; means for adjusting said alining-bar laterally upon the base-section; side blocks engaging the alining-bar provided with means for adjustment longitudinally of said bar; a dimensioning-gage interposed between said side bars; mold-blade movable between the side blocks.

12. A type-mold such as described provided with a mold-cavity the casting-surface of which is slightly roughened as and for the purpose set forth.

13. In a type-mold such as described, the combination to form the mold-cavity, of a rough-faced side block, a smooth-faced side block, a rough-faced mold-blade, and a smooth-faced cross-blade or opposing wall.
